UNITED STATES PATENT OFFICE.

JOHN D. KNEEDLER, NIAL VAN SICKLE, BUEL COUCH, AND NELSON T. HANSON, OF SIOUX CITY, IOWA.

DEVICE FOR BRIDGING AND UNITING RAILS.

No. 821,508.

Specification of Letters Patent.

Patented May 22, 1906.

Application filed October 2, 1905. Serial No. 281,018.

To all whom it may concern:

Be it known that we, JOHN D. KNEEDLER, NIAL VAN SICKLE, BUEL COUCH, and NELSON T. HANSON, citizens of the United States, residing at Sioux City, in the county of Woodbury and State of Iowa, have invented certain new and useful Improvements in Devices for Bridging and Uniting Rails; and we do hereby declare the following to be a full, clear, and exact description of the invention, such as will enable others skilled in the art to which it appertains to make and use the same.

Our invention relates to devices for bridging and binding rails; and its object is to provide a simple device which will securely fasten the ends of rails together and which permits said rails to be rigidly and firmly fastened to a tie, so as to prevent spreading.

Another object is to provide means whereby the wheels of a car will be supported out of contact with the ends of the rails when passing thereover, so that pounding will not result.

The joint comprises two clamping-plates adapted to be fitted between the base-flanges and heads of rails where their ends abut, and these plates have lips which are adapted to rest upon a tie and to be secured thereto by a plurality of fastening means. The clamping-plates are fastened to the rails in the usual manner, and disposed upon the outer one of these plates is a bridging-plate having a curved edge which extends a short distance above the heads of the rails at their ends and is adapted to support the wheels of cars as the same pass over the joint.

The invention also consists of certain other novel features of construction and combination of parts, as will be hereinafter more clearly set forth, and pointed out in the claim.

In the accompanying drawings, we have shown the preferred form of our invention.

In said drawings, Figure 1 is a perspective view showing the ends of two rails secured in place by means of our improved fastening device. Fig. 2 is a transverse section through one of the rails and showing the joint in elevation and a wheel thereon. Fig. 3 is a detail view of the bridging-plate; and Fig. 4 is an end elevation of a modified form of clamping-plate, showing the bridging-plate integral therewith.

Referring to the figures by numerals of ref-

erence, 1 and 2 are clamping-plates which are adapted to fit snugly between the heads 3 and 55 the base-flanges 4 of the rails, and these plates are held tightly against the webs 5 of the rails and upon the flanges 4 and heads 3 by means of bolts 6, which extend through elongated slots in the plates and rails. Both 60 of the clamping-plates are similar in construction and have integral lips 7 at the centers thereof, the bottoms of which lie in the same plane as the lower edges of said plates. These lips are substantially equal in width to 65 the width of a tie and have a series of openings 8 therein adapted to receive bolts, spikes, or other fastening devices. (Not shown.) By employing lips such as herein shown and described the entire device can be fastened 70 to a single tie by means of several fastening devices, and it therefore becomes unnecessary to place two or more ties together directly under the joint. The bolts 6 also extend through a bridging-plate 9 and serve to 75 clamp it upon the outer clamping-plate 2. This plate 9 has a base-flange 10, which bears upon the lower portion of plate 2, and the upper surface of plate 9 is curved at its outer edge, as shown at 11, while the inner edge of 80 this surface is straight, as shown at 12. This upper surface is inclined toward the rail, as seen best in Fig. 2, so that the tendency is to prevent spreading at the joint by serving to force the wheel inward toward the rail. The 85 bevel which is thus produced at the center of the plate and opposite the ends of the rails is equal to the reverse bevel of the car-wheel, so that when a wheel passes over the rails it will be supported entirely by plate 9 for a short 90 distance while passing over the rail ends. Said wheels will not, therefore, pound in passing over the rail ends.

By utilizing the lips 7 the cost of securing the rails together is reduced to the minimum 95 for the reason, as before stated, that it is unnecessary to provide any special arrangement of ties. Moreover, as the lips are located directly beside the ends of the rails, and are fastened by a plurality of devices, there is no danger of the rails spreading at this point.

In lieu of forming the bridging-plate 9 and clamping-plate 2 in two pieces they can be formed integral, as shown in Fig. 4.

Having thus fully described our invention,

what we claim as new, and desire to secure by Letters Patent, is—

In a rail-joint the combination with adjoining rails, of clamping-plates disposed upon opposite sides of said rails opposite the joint therebetween and having lateral integral lips with spike-receiving openings, said plates fitting snugly between the heads and the base-flanges of the rail, a bridging-plate separate from the clamping-plate and having a base-flange resting upon the flange of one of the clamping-plates and having its upper face convex from end to end and the inner edge of said upper face straight, the ends of said upper face being disposed below the tops of the rails and the center of said face projecting above the rails and beveled from side

to side upward away from the rails, the vertical face of said bridging-plate bearing against the face of the rail and of the adjacent clamping-plate, and securing means extended through the rail, the clamping-plates, and the bridging-plate and securing the whole together. 20

In testimony whereof we have signed our names to this specification in the presence of two subscribing witnesses.

JOHN D. KNEEDLER.
NIAL VAN SICKLE.
BUEL COUCH.
NELSON T. HANSON.
